Inventor.

Wm O. Leslie,

United States Patent Office.

WILLIAM O. LESLIE, OF PHILADELPHIA, PENNSYLVANIA.

Letters Patent No. 67,439, dated August 6, 1867.

IMPROVED BRICK MACHINE.

The Schedule referred to in these Letters Patent and making part of the same.

TO ALL WHOM IT MAY CONCERN:

Be it known that I, WILLIAM O. LESLIE, of the city of Philadelphia, in the State of Pennsylvania, have invented a new and useful Brick Machine; and I do hereby declare the following to be a full and exact description of the construction and operation of the same, reference being had to the annexed drawings, forming part hereof, in which drawings—

Figure 1 is a perspective view of the machine, the other figures representing parts detached, viz:

Figure 2 is a vertical section of the mixing-tub, showing some of the parts enclosed by it in section, showing the double screw at the bottom of the tub in perspective, and showing an end elevation of the mould-plungers, with their respective friction-wheels.

Figure 3 is a perspective view of the eccentric, and of a part of the connecting levers by which a reciprocating motion is given to the mould-carriage.

Figure 4 is a perspective view of the track upon which the friction-wheels of the mould-plunger travel, showing an inclined plane at each end of said track, with intermediate curved projections.

Figure 5 is a transverse vertical section of the bed-plate upon which the mould-carriage slides, also of the pressure-plate, the mould-carriage, a mould, mould-plunger, friction-wheel, and also of the track upon which said wheels travel.

Figure 6 is a perspective of the pressure-plate, showing the shape of the two apertures therein, and the ends of the knives.

Figure 7 is an enlarged perspective view of the mould-plunger.

To enable others skilled in the art to make and use my invention, I will proceed to describe its construction and mode of operation.

In fig. 1, *a* is the foundation of the machine. The parts marked *b* are the frames to support the gearing; *c* is the mixing-tub; *d* is a shaft, without vertical support at its lower end, being suspended from and having a bearing in the cross-beam *e*. The shaft *d* has rigidly attached to it the radial toothed levers *f*, knives *g*, and the double screw *h*. There are four stationary toothed arms *i*, which are attached to the sides of the tub, only two of said arms appearing in the section. These arms all proceed radially from a hub or centre through which shaft *d* passes. On shaft *d* there is a bevel cog-wheel, *j*, which gears into another bevel cog-wheel *k* on the shaft *l*, which also carries the bevel cog-wheel *m*, which gears into the bevel cog-wheel *n* on one end of the shaft *o*, which at its other end has a cog-wheel, *p*. There are two other cog-wheels similar to *p*, arranged in line below *p*, the lowermost of the series being on one end of the driving-shaft *q*. *r* is an eccentric on the driving-shaft *q*. Said eccentric is connected by a loose joint to the lever *s*, which is connected with the rod *t*, which is connected with the mould-carriage *u*. *v v'* are the bed-plates upon which the mould-carriage *u* slides. *w w' w'' w'''* are the moulds; *x x' x'' x'''* the mould-plungers. Each plunger is provided with a friction-wheel *y*. *z* is the track, extending between and parallel to the bed-plates *v v'*. The friction-wheels *y* move upon the track *z*. Each of the mould-plungers *x x' x'' x'''* is faced with felt or heavy cloth of wool, as shown in fig. 7, the object being to facilitate the removal of the bricks from the plungers when the bricks are ready for delivery, and to obviate the necessity of using sand or oil. I prefer to make the plungers of cast iron, and to fasten the felt or cloth to the face thereof with plumbers' solder. *1* is the pressure-plate, which is fastened on the top of the bed-plates *v v'*. This plate *1* has in it two apertures *2* and *3*, formed as shown in fig. 6. The lower side of plate *1* is made convex, and the upper side of the mould-carriage is made correspondingly concave, as shown in fig. 5. *4* and *5* are knives, the edges of which have a convexity corresponding to that of plate *1*, and I prefer to set them in said plate diagonally. They are of steel, made to fit and slide each into an aperture, *6*, slightly tapered on the sides, so as to be firm, and also removable, as occasion may require.

The operation of the machine may be described as follows: The mixing-tub *c* is first filled with clay, as it is dug from the pit, and then the machine is set in motion. The clay is thoroughly crushed or broken into small particles, and partially mixed by the action of the toothed radial levers *f* and the stationary toothed arms *i*. It is still further mixed and is pressed downward by the knives *g*, the blades of which are adjustable, being set horizontal, or with more or less obliquity, to suit the quality of the clay. These knives thus perform the double office of mixing the clay and pressing it downward until it is acted upon by the double screw *h*, which

forces it into the moulds $w w^1 w^2 w^3$, filling them as they are presented. There are two or more moulds in each end of the carriage u , which has given to it by the eccentric r a reciprocating motion whereby the moulds in one end and those in the other end of the carriage are alternately brought under the screw h to be filled. While the moulds in one end are being thus filled, those in the other end of the carriage have passed from under the pressure-plate, and are in position to deliver their bricks. The plungers $x x^1 x^2 x^3$, when made of iron, have considerable weight; they fit the moulds closely, and move freely therein in a vertical direction, as the plungers pass along on the track, their own gravity being sufficient to give them the necessary downward motion, while their upward motion is given to them by the projections 7 8 9 10 on the track. As soon as the moulds $w w^1$ are filled, the carriage u starts towards the place of delivery for these moulds; the clay in said moulds then receives its first pressure against the convex surface of the pressure-plate, by reason of the projection 7. As the moulds pass under the aperture 2, the clay is relieved from pressure, and rises a little in the moulds; the knife 4 shaves off the superfluous clay as the moulds pass under it; the clay in the moulds then receives a second pressure, which is occasioned by the projection 8; the plungers are finally again forced up, and kept up by the inclined plane 11 at the end of the track, flush with the top of the track, and the brick delivered in a finished state. A similar action takes place in regard to the moulds $w^2 w^3$, which, when filled, pass in an opposite direction over the projections 9 and 10 and inclined plane 12. While they are being filled, the moulds have a slight pause, which is occasioned by the loose joint shown in fig. 3, by which the eccentric r is connected with the lever s . All the parts of the machine except as otherwise specified are made of iron.

Having thus described my invention, I claim, and desire to secure by Letters Patent—

1. The mould-carriage u , constructed and operating substantially as shown and described.
2. The pressure-plate 1, constructed and operating substantially as shown and described.
3. The track z , constructed and operating substantially as shown and described.
4. Making the under side of the pressure-plate 1 convex, and the upper side of the mould-carriage u correspondingly concave, substantially as shown and described.

WM. O. LESLIE.
